TABLE SHRINE

Scott A. Brockway, Venice, Calif.

Application August 31, 1951, Serial No. 244,520

1 Claim. (Cl. 312—204)

1

This invention relates to furniture, and more particularly, has reference to an article of furniture formed in the simulation of a building, and adapted to serve as a table or desk, as well as a repository for various objects.

It is well appreciated by those fully conversant with the art of furniture design that, particularly in the design and construction of children's furniture, attractive and unusual furniture pieces have considerable appeal for prospective purchasers. In this connection, it has been found desirable to form various articles of children's furniture in the simulation of objects ordinarily not found in the field of furniture, it being true that in such instances not only does the unusual appearance of the furniture increase its basic appeal to a purchaser, but also, the article of furniture is made usable as an educational aid, wherein the child is enabled to gain knowledge of the object simulated.

To this end, it is an important object of the present invention to provide an article of furniture in the nature of a combined cabinet and writing desk, novelly formed to simulate faithfully a building such as a church or temple.

It is another important object to incorporate, in said article of furniture, features of construction whereby one or more component parts thereof can be shifted or adjusted to different positions in a manner to change substantially the appearance of the building simulated, thus to educate the child as to the construction and appearance of more than one building.

Yet another object is to provide an article of furniture as stated that will be capable of being manufactured at little or no increase in cost above that which would be required for constructing a combined cabinet and desk not having the features mentioned.

Referring to the drawings:

Figure 1 is a front elevational view of an article of furniture formed in accordance with the present invention;

Figure 2 is a side elevational view;

Figure 3 is a top plan view;

Figure 4 is a sectional view taken on line 4—4 of Figure 1;

Figure 5 is a sectional view taken on line 5—5 of Figure 1;

Figure 6 is a rear elevational view; and,

Figure 7 is a front elevational view, a portion of the article of furniture being shifted to simulate a building different from that illustrated in Figure 1.

Referring to the drawings in detail, the article of furniture formed in accordance with the present invention includes a plurality of upstanding legs 1, disposed at the several corners of said article, and formed to any desired ornamental configuration. At their upper ends, the legs 1

2

are rigidly connected, in any suitable manner well known in the art, to the corner portions of an open-rectangular base frame comprising a plurality of frame pieces 2 fixedly joined at their respective ends to form the desired base frame of rectangular configuration.

Disposed exteriorly of and secured fixedly to the base frame is a rectangular base including a vertically disposed rear wall 3, side walls 4 secured at their rear edges to opposite ends of the rear wall, and a front wall 5 secured at opposite ends to the front edges of the side walls. The front wall 5 is provided with a drawer opening, receiving a conventionally formed drawer generally designated 6, that slides into and out of the base on guides 7 secured to the inner surfaces of the parallel side walls 4. The drawer 6 is provided with one or more drawer pulls, and may be used as a repository for any desired object or objects.

The base includes a flat, horizontally disposed, rectangular top portion 8, fixedly secured to the side and rear walls of the base, and projecting a slight distance forwardly beyond the front wall 25 of the base, as readily seen from Figure 4.

Extending upwardly from and fixedly secured to the rear edge of the top portion 8 is the back wall 9 of a cabinet portion, this being connected along its opposite side edges to the rear edges 30 of vertically disposed side walls 10 of the cabinet portion, which are in turn secured along their front edges to a front wall 11 of the cabinet portion, by means of tongue and groove connections as illustrated in Figure 5, or by any other means 35 known to the art.

The front wall 11 is provided with a large opening 12, providing access to the interior of the cabinet portion, and normally closing this opening is a door 13 of corresponding appearance and 40 dimensions, the door 13 being hinged at its lower edge to the top portion 8, by means of hinges 14 or their equivalents. A handle 15 is preferably provided upon the door, for convenience in shifting the door to open and shut positions. In

Figure 4, the door is illustrated in its closed position in full lines, but as will be noted from Figure 4, when the door is swung to its open position, it extends approximately horizontally, and is supportedly positioned upon the top portion 8 45 of the base, extending forwardly beyond the base to provide a desk member.

A horizontal partition 16 is mounted within the cabinet portion of the article of furniture, adjacent the upper end thereof, to provide an upper compartment in said cabinet portion. The upper compartment is closed at its top by a horizontally disposed top member 17 secured to the side and rear walls of the cabinet portion, and by an upwardly swinging lid 18, connected to the top member 17 by hinges 19. The lid 18, when

3

swung upwardly, provides access to the top compartment of the cabinet portion.

Medially located between opposite sides edges of the back wall 9 of the cabinet portion is an opening 20, said opening being spaced a short distance below the top of the cabinet portion, as best seen from Figure 4. A bolt 21 extends through the opening 20, and through an opening 22 registering with the opening 20, and formed in a back piece generally designated 23 15 through the bolt 21 forming a horizontal axis. The opening 22 is formed intermediate opposite ends of the back piece 23, said back piece being disposed in a vertical plane and in sliding face to face contact with the exterior surface of the back wall 9. A wing nut 24 is threadable upon the bolt 21, so as to clamp the back piece to the cabinet portion in selected positions to which the back piece is rotatably adjusted upon the bolt 21.

At opposite ends, the back piece 23 is formed in the simulation of the gable portions of a building. Thus, by reference to Figure 1, it may be noted that at one end, the back piece is in the simulation of the gable portion of a church including a steeple, this end of the back piece being designated 25 and being opposite the end 26 of the back piece. In the present instance the end portion 26 of the back piece is formed in the simulation of the gable portion of a temple.

The gable simulations extend from locations adjacent the pivotal connection 21, toward the opposite ends of the back piece, and are so formed upon the back piece as to cause one of the simulations to be wholly concealed by the rear wall 9 of the cabinet portion when the other simulation is being exposed above said cabinet portion. However, if it is desired that the particular gable portion that is concealed be substituted for that which is being exposed, it is merely necessary to loosen the wing nut 24, after which the back piece is swung through one-hundred eighty degrees, and the wing nut tightened once again.

On the outer surface of the door, there is painted or otherwise formed the simulation of building windows 27, and a building entrance 28. These cooperate with the back piece to impart to the entire cabinet portion above the base the appearance of a building structure of a selected architectural design.

In this way, a valuable educational aid is incorporated in the article of furniture. Obviously, the building simulated can be any particular

building, including well known buildings of which the child should have knowledge. By incorporating the appearance of such a building in the article of furniture described, the child obtains intimate knowledge of the general appearance of the building. By reversing the back piece end for end, a different building is simulated, and thus, the child is enabled to gain knowledge of more than one building. At the same time, the article of furniture has considerable utility, both as a cabinet and as a desk, and has in addition the desirable characteristics of being basically novel and attractive in appearance.

What is claimed is:

An article of furniture including a base; a box-like structure mounted upon the base to extend upwardly therefrom and having a back wall and an opening in the front wall thereof; a door providing access to the interior of the structure and hinged mounted thereupon to swing into and out of position in said opening, said door when swung out of the opening being supportedly positioned upon the base to extend substantially horizontally and outwardly thereof to provide a desk member, the door being formed in the simulation of a building front to impart the appearance of a building to said structure in the closed position of the door; and an upstanding back piece arranged in face to face sliding contact with the back wall of said structure and pivotally connected intermediate its ends to the back wall of said structure for rotation about a horizontal axis between opposite positions one-hundred eighty degrees apart, said ends of the back piece being respectively exposed in said opposite positions of the back piece above said structure and being formed to simulate gable portions of the building simulated upon the door.
